UNITED STATES PATENT OFFICE.

PETER E. MALMSTRÖM AND PAUL E. DUMMER, OF NEW YORK, N. Y.

APPARATUS FOR THE MANUFACTURE OF BEVERAGES.

SPECIFICATION forming part of Letters Patent No. 395,244, dated December 25, 1888.

Application filed August 3, 1888. Serial No. 281,859. (No model.)

To all whom it may concern:

Be it known that we, PETER E. MALMSTRÖM and PAUL E. DUMMER, both citizens of the United States, residing at New York, in the 5 county and State of New York, have invented new and useful Improvements in Apparatus for the Manufacture of Effervescent Beverages, of which the following is a specification.

This invention relates to an improvement in 10 the manufacture of effervescent or carbonated beverages, as set forth in the following specification and claims, and illustrated in the accompanying drawings, in which—

Figure 1 is a front elevation of a device for 15 manufacturing effervescent beverages. Fig. 2 is a section along the line $x-x$, Fig. 1.

Similar letters indicate corresponding parts.

In the drawings, the letter A indicates a 20 feeding-vessel. A series of feeding-vessels is shown, so that one vessel can be put at rest or be filled while another is being operated or emptied. Suitable openings or inlets, B, closed by covers or caps, can be used for filling the feeding-vessels with water or suitable liquid. 25 Safety-valves C and pressure-gages D can be applied to the feeding-vessels. A gas-supply, E, is shown communicating with a branch, F. By opening the valve G gas under pressure can be forced through the spray-pipe or jet- 30 pipe H, extending into the interior of the feeding-vessel, so that the gas is thoroughly mixed with and dissolved in the liquid in the feeding-vessel A.

By opening the valves K M the liquid in 35 the feeding-vessel will be fed through the conduit I L onto the shelves N in the charging-vessel P. The shelves N are alternately inclined, so that the liquid will flow back and forth until it reaches the dish O. After fill- 40 ing the dish O the liquid overflows and passes to the bottom of the charging-vessel.

The gas-supply E communicates by a 45 branch, Q, with the charging-vessel P, and by opening the valve R the gas is made to pass into the charging-vessel and mixes with the liquid flowing back and forth along the shelves N.

From this description it will be seen that 50 the liquid becomes charged with gas in the feeding-vessel, and this charged liquid passes over the shelves N in the charging-vessel P,

where it absorbs an additional quantity of gas, so that it becomes thoroughly saturated with gas before being fed through the valve T into siphons or other suitable receptacles. 55

By referring to Fig. 1 it will be seen that a series of feeding-vessels are provided, each of which communicates with the gas-supply E and with the charging-vessel P, and each of which can be shut off without disturbing the 60 communications of the remaining feeding-vessels. By this arrangement the charging-vessel P can be constantly supplied with liquid previously charged with gas in one of the feeding-vessels, and the operation of drawing 65 the liquid fully charged with gas from the charging-vessel P into siphons or other receptacles can be carried on without interruption.

What we claim as new, and desire to secure 70 by Letters Patent, is—

1. The combination of a feeding-vessel, A, a charging-vessel, P, a gas-supply pipe, E, a spray-pipe, H, connected with the gas-supply pipe and leading into the interior of the feeding-vessel to spray the gas within the body of liquid, a branch pipe, Q, leading downward directly from the gas-supply pipe below the spray-pipe and opening into the charging-vessel to supply the liquid therein with an additional charge of gas, a pipe, L, connecting the lower portion of the feeding-vessel with the upper part of the charging-vessel to continuously conduct the gas-charged liquid from the feeding-vessel into the charging-vessel, 85 and a discharge-valve, T, substantially as described.

2. The combination, with a feeding-vessel, A, a charging-vessel, P, containing a series of zigzag trays, N, a gas-supply pipe, E, a spray-pipe, H, connected with the gas-supply pipe and leading into the interior of the feeding-vessel to spray the gas within the body of the liquid, a branch pipe, Q, leading downward directly from the gas-supply pipe below the 90 spray-pipe and opening into the charging-vessel to supply the liquid flowing over the trays therein with an additional charge of gas, a pipe, L, connecting the lower portion of the feeding-vessel with the upper part of the 95 charging-vessel to continuously conduct the gas-charged liquid from the feeding-vessel 100 over the shelves N in the charging-vessel P,

into the charging-vessel above the trays, and a discharge-valve, T, substantially as described.

3. The combination, with a series of feeding-vessels, A, and with a single charging-vessel, P, of a gas-supply, E, spray-pipes II, extending from this supply-pipe, one into the interior of each of the feeding-vessels, a pipe leading from said supply-pipe into the charging-vessel, a pipe, I, communicating with the several feeding-vessels near their bottoms and with the charging-vessel near its top, suitable stop-cocks for shutting off each of the feed-

ing-vessels without disturbing the communication of the remaining feeding-vessels, and a discharge-valve, T, substantially as described.

In testimony whereof we have hereunto set our hands and seals in the presence of two subscribing witnesses.

PETER E. MALMSTRÖM. [L. S.]
PAUL E. DUMMER. [L. S.]
